(Cl. D14—6)

To all whom it may concern:

Be it known that I, Howard A. Lipe, a citizen of the United States and a resident of the District of Columbia, have invented a new, original, and ornamental Design for a Gearshift Lever Knob, of which the following is a specification, reference being had to the accompanying drawing, forming part thereof.

Figure 1 is a plan view of a gearshift lever knob, showing my new design.

Figure 2 is a bottom view of said knob.

Figure 3 is an inner end view of the knob.

Figure 4 is an outer end view of the knob.

Figure 5 is a side elevational view of the knob.

I claim:

The ornamental design for a gearshift lever knob, as shown.

HOWARD A. LIPE.
